UNITED STATES PATENT OFFICE.

JOHN W. GRONROS, OF BRONX, NEW YORK.

SPRINKLER HEAD.

Application filed March 31, 1920. Serial No. 370,112.

To all whom it may concern:

Be it known that I, JOHN W. GRONROS, a citizen of Finland, residing at 1030 Kelly St., in the county of Bronx and State of New York, have invented certain new and useful Improvements in Sprinkler Heads, of which the following is a specification.

This invention relates to automatic fire extinguishers, and more particularly to 10 sprinklers, the valves of which are held closed by fusible locks.

The object of the invention is to provide means whereby the sprinkler head valves are quickly released by a small flame there- 15 by preventing a fire from gaining dangerous and damaging progress.

Another object is to provide simple, safe and efficient valve locking means, fusible at low temperature to release the sprinkler 20 head valves immediately a fire is started.

With the foregoing and other objects in view, which will appear as the description proceeds, the invention resides in the combination and arrangement of parts and in the 25 details of construction hereinafter described and claimed, it being understood that changes in the precise embodiment of the invention herein disclosed may be made within the scope of what is claimed without 30 departing from the spirit of the invention.

In the accompanying drawings:—

Figure 1 represents a side elevation of a 35 sprinkler head with this improved extinguisher shown applied, parts being in section.

Figure 2 is a horizontal section taken on the line 2—2 of Fig. 1, and

Figure 3 is a detail vertical section.

In the embodiment illustrated, a water 40 supply pipe P is shown which is charged with water under pressure in the usual and well known manner. Usually a plurality of such pipes is arranged in parallel relation, a suitable distance apart and supported 45 by suitable hangers to the ceiling or other part of the building to be protected against conflagration. This supply pipe P is provided with discharge nozzles N one of which only is here shown and which are normally held closed by suitable valves V retained in their closed position by a strut 2 mounted in a supporting frame 1.

The supporting frame 1 here shown, is made triangular in form, being removably 50 mounted on the nozzle N. In this frame 1 is mounted the strut 2, which is here shown

in the form of a duplex cone, the points of which are engaged respectively with the apex of the frame 1 and with the valve V as shown at 3 and 4. The point 4 which rests on the valve is constructed of fusible material and is here shown mounted in a seat 5 formed in said valve V. This point 4 is fusible at a moderate temperature of about 180° Fahrenheit more or less.

Arranged around the fusible point 4 on the valve V is a slow burning element 6 constructed of any suitable material. This element 6 is here shown in the form of an open loop and is spaced from the point 4 a sufficient distance to permit the material flowing from the melted point to spread out and thereby release the strut 2 so that when said strut drops out of the frame 1 the pressure of the water within the pipe will displace 75 the valve V and discharge the water into the surrounding atmosphere to extinguish the fire.

A readily inflammable strip 7 is connected with the slow burning element 6 and depends therefrom into the room in which the device is mounted and may be of any desired length according to the position of the extinguisher.

When this inflammable member 7 takes 85 fire the flame will readily spread and ignite the slow burning element 6 and generate sufficient heat to melt the fusible point 4 and release the valve V.

A wire 8 of non-fusible material is secured 90 at one end to the pipe P as shown at 9 and has its other end secured to the loop shaped element 6, so that in case the member 7 should be ignited when there is no fire in the room, a pulling force may be exerted on 95 the wire 8 thereby disengaging the loop shaped fusible member 6 from the sprinkler head and preventing release of the valve. When such a pull is exerted the member will drop into the dotted line position shown in 100 Fig. 1 and may be replaced after the member 7 has been extinguished.

From the above description it will be obvious that this device while simple in construction and cheap to manufacture may be 105 easily applied to a sprinkler head already in use and that it will operate efficiently to release the sprinkler head valve for extinguishing a fire.

From the foregoing description, taken in 110 connection with the accompanying drawings, the advantages of the construction and of

the method of operation will be readily apparent to those skilled in the art to which the invention appertains and while I have described the principle of operation of the 5 invention together with the device which I now consider to be the best embodiment thereof, I desire to have it understood that the device shown is merely illustrative and that such changes may be made as are 10 within the scope of the claimed invention.

Having thus fully described my invention what I claim as new and desire to secure by Letters Patent, is:—

1. The combination with a fusible locking element; of a slow burning element associated with said lock with a readily inflammable member connected with said element, and a non-fusible member fastened to said slow burning element to provide for the removal of said element when necessary.

2. The combination with a fusible lock; of

an inflammable element arranged adjacent said lock; and manually controlled means connected to remove said element from the vicinity of said lock when desired.

3. The combination with a fusible lock; of an open loop shaped inflammable element encircling said fusible lock.

4. The combination with a fusible lock; of a hook shaped inflammable element partially encircling said fusible lock, said hook shaped inflammable element having an open mouth to facilitate attachment with and detachment from said fusible lock and to permit the flow of fused lock material from the 35 melted fusible lock.

In testimony whereof I affix my signature in presence of two witnesses.

JOHN W. GRONROS.
